FAN CONSTRUCTION

George L. Moeller, St. Louis, Mo., assignor to
 Knapp-Monarch Company, St. Louis, Mo., a
 corporation of Missouri

Application August 12, 1940, Serial No. 352,291

3 Claims. (Cl. 230—259)

My present invention relates to a fan construction for electric air circulating fans and the like, having certain improvements effective to cause the motor to run considerably cooler than with the usual type of fan.

One object of the invention is to provide such a fan construction of simple and durable construction which can be inexpensively manufactured.

More particularly, an object of my invention is to provide a fan element with propeller blades and so designed adjacent the center of the element that a blower element may be installed at this point so that it is effective to draw air through the motor and discharge such air into the stream of air being circulated by the propeller blades of the fan construction.

Another object is to provide a fan element having propeller blades and a blower element consisting of a disc with blower blades formed therefrom and both the fan element and blower element being assembled on a hub that secures the two together and that mounts them on the shaft of the motor.

With these and other objects in view, my invention consists in the construction, arrangement and combination of the various parts of my device whereby the objects contemplated are attained, as hereinafter more fully set forth, pointed out in my claims and illustrated in the accompanying drawings, in which:

Figure 1 is a rear elevation of a fan construction embodying my invention, the shaft on which the fan is mounted being shown in section.

Figure 2 is a sectional view on the line 2—2 of Figure 1 and showing the fan mounted on a motor shaft, the shaft being illustrated in vertical position, although the fan may be used in either this position or in the usual position with the shaft substantially horizontal.

Figure 3 is a perspective view of the blower element of my fan construction.

Figure 4 is a view similar to Figure 1, showing a slightly modified construction.

Figure 5 is a sectional view on the line 5—5 of Figure 4.

Figure 6 is another view similar to Figure 1, showing a further modified construction.

Figure 7 is a sectional view on the line 7—7 of Figure 6.

On the accompanying drawings I have used the reference character F to indicate a fan element and B a blower element. The fan element F consists of a central disc-like portion 10 which is dished by providing an annular flange 12

thereon. The free edge of the flange 12 terminates in a plurality of propeller blades 13.

The blower element B consists of a disc 14 slightly smaller than the dished portion 10 and located within the flange 12. The disc 14 has a plurality of blower blades 15 formed by cutting the disc as indicated at 16, and bending each cut-out portion to a position at substantially right angles to the plane of the disc.

The fan and blower elements F and B are assembled on a hub 17 against a shoulder 18 thereof after which the end of the hub is peened over as at 19 to retain the elements F, B and 17 in assembled relation to each other.

The hub 17 is adapted for mounting on a motor shaft 20 and may be secured thereto as by a set screw 21. The shaft 20 extends from a motor M, the housing of which may be provided with air circulating openings 22.

In Figure 4, I show a modified construction wherein the fan element is indicated as F¹, and the blower element as B¹. The numbered elements are similar to Figures 1, 2 and 3, and accordingly bear the same reference numerals with the addition of a.

It will be noted that there are more of the blower blades 15^a and that they are somewhat smaller in area when compared with Figure 1. Such a change is made so as to design the blower element B¹ for a higher speed of rotation and a propeller blade 13^a of less pitch.

In Figures 6 and 7 I show a modified construction wherein there are fan elements 10^b, 13^b and 14^b mounted on a hub 17^b. The fan elements 10^b and 14^b are of sheet metal construction and the element 10^b is slotted as at 23 to receive the propeller blade 13^b. The propeller blade is formed of rubber so that it will bend when striking an object without damaging such object.

In the form of invention shown in Figures 6 and 7 the blower blades 15^b are cut out as indicated at 16^b directly from the fan element 14^b and bent to a position at substantially right angles to the plane of the disc-like fan element 14^b.

Practical operation

In the operation of my fan construction the blower blades 13 circulate air as indicated by the arrows 24 in Figure 2. The direction of circulation is substantially parallel to the axis of rotation of the shaft 20.

The blower blades 15 draw air from the motor M as through openings 22 as indicated by the arrows 25. Due to centrifugal action the blades 15 create a substantial vacuum adjacent the hub

17, thus causing the flow of air indicated by the arrows 25. This air is then thrown centrifugally outwardly as indicated by the arrows 26 and finally into the stream of circulated air as indicated by the arrows 27.

In actual practice I have found that the inclusion of the blower blades 15 at the center of the fan element F will cause the motor M to run in the neighborhood of thirty-five per cent (35%) cooler. The efficiency of the fan structure as an air circulating means is not in any way reduced by my construction.

Some changes may be made in the construction and arrangement of the parts of my device without departing from the real spirit and purpose of my invention, and it is my intention to cover by my claims any modified forms of structure, or use of mechanical equivalents, which may be reasonably included within their scope.

I claim as my invention:

1. In a fan construction, a sheet metal fan element having a central, forwardly embossed part, a shaft for said fan element, said fan element having propeller blades for circulating air substantially longitudinally of said shaft, a motor for rotating said shaft and means for drawing air through said motor to cool the same comprising a central imperforate disc portion of said fan element having blower type blades partially counter sunk in said embossed part and effective to circulate air from adjacent said shaft outwardly beyond the periphery of said embossed part to mix with the air stream through the propeller blades.

2. In a fan construction of the character disclosed, a shaft, a hub element thereon, a fan ele-

ment comprising a central dished portion and propeller blades projecting from the periphery thereof for circulating air substantially longitudinally of said shaft, a motor for rotating said shaft and means for drawing air through said motor to cool the same comprising a blower element including a bladed disc element adjacent said dished portion of said fan element, said disc element to serve as a blower to effect movement of air outwardly from said shaft to mix with the air stream through said propeller blades, said fan element and said disc element being mounted against a shouldered portion of said hub element and the end of said hub element being peened over said fan and disc elements to retain them assembled with relation to said hub element.

3. In a fan construction of the character described, a shaft, a fan element thereon comprising a central dished portion and propeller blades projecting from the periphery thereof for circulating air substantially longitudinally of said shaft, a motor for rotating said shaft and means for drawing air through said motor to cool the same comprising a blower element located in said dished portion of said fan element, said blower element effecting movement of air outwardly from said shaft to mix with the air stream through said propeller blades, a hub on said shaft, said fan and blower elements being mounted against a shouldered portion thereof and the end of said hub element being peened over said elements to retain them assembled with relation to said hub.
